UNITED STATES PATENT OFFICE.

JULIUS KONEGEN, OF BRUNSWICK, GERMANY.

PLAN SIFTER.

SPECIFICATION forming part of Letters Patent No. 726,073, dated April 21, 1903.

Application filed May 14, 1902. Serial No. 107,295. (No model.)

To all whom it may concern:

Be it known that I, JULIUS KONEGEN, engineer, a subject of the Emperor of Germany, residing at Brunswick, Duchy of Brunswick, 5 Empire of Germany, have invented certain new and useful Improvements in or Connected with Plan Sifters, of which the following is a specification.

This invention relates to plan sifters; and 10 the objects of the same are to improve, simplify, and cheapen the construction of this class of devices.

To the foregoing and other ends my invention consists of the details of construction and 15 novel combination of parts hereinafter particularly described.

Referring to the accompanying drawings, forming a part of this specification, Figure 1 is a side elevation illustrating a form of device which my invention aims to improve. 20 Fig. 2 is a plan view of the construction shown in Fig. 1. Fig. 3 is a plan view of my improved plan sifter. Fig. 4 is a detail sectional view illustrating one method I may employ of attaching the draw-rods to the side bars of the frame. Fig. 5 is a detail plan illustrating one means of retaining the sieves in the frame; and Fig. 6 is a view similar to Fig. 5, illustrating another means of retaining 25 the sieves in the frame.

Of recent years a form of plan sifter such as is shown in the accompanying drawings has come more largely into use in which a main frame *a*, made of wood of the shape shown in plan view in Fig. 2, is suspended in the ordinary manner on four suspension members or rods *b* and is set in oscillating motion from a belt-pulley *c* by means of a crank engaging with it as nearly as possible 30 at its center of gravity. This main frame incloses two series of shallower sifting-frames *d*, which are inserted in the main frame so far as the height of its sides allows, after which several further frames are placed above 35 and below those mounted in the main frame and are united with the main frame and with one another by means of anchor-like screw attachments. In Fig. 2 these sifting-frames are only shown as inserted on the left-hand 40 side, while the right-hand side of the main frame is vacant. With this arrangement the insertion and withdrawal of the sifting-frames

is somewhat inconvenient, and, further, the sifting-frames, which are directly inclosed by the main frame, must be of several millimeters smaller dimensions than the clear width of the inclosing framework, as they otherwise could only be inserted with difficulty, and this small difference between the inclosing and the inclosed sides produces vibration and knocking during the working. 55 The arrangement of frames which forms the object of the present invention is intended to avoid these drawbacks. It has the form shown in Fig. 3. It is preferably made of iron—for example, of U-iron—instead of wood. It is characterized by merely consisting of two long sides *f*, connected in the middle by a cross-bar *g*, but not united at the ends into a closed frame, the narrow ends of the frame thus being absent. The two lowest sifting-frames *d* are firmly suspended on hanging rods *e*, 60 Fig. 1, the other frames being laid upon these, and as the main frame is open at the ends (Fig. 3, right-hand side) the sieve-frames 65 may be inserted from the ends without any difficulty.

In order to produce the firm connection between the sieve-frames and the main frame necessary for working, tightening-screw draw-rods *h* are employed, which when their nuts *i* are screwed up cause the spring-iron side bars *f* of the main frame to approach one another and to press firmly against the sieve-frames *d*. When the nuts *i* are turned in the 70 opposite direction, the side bars *f* open either by their spring-power or compulsorily, when an arrangement is adopted in which the nut is rotatably connected to the side bars, as shown on an enlarged scale in Fig. 4. In 75 this arrangement each draw-rod *h* passes through the U-shaped side bars *f* of the main frame, and its nut *i* has a ring *k*, over which an annular part *l*, secured to the U-irons *f*, engages. In this arrangement the nut *i* carries the side bar *f* with it in both directions 80 of movement.

If in spite of the fact, as experiments have shown, that the clamping in the arrangement hereinbefore described is in every way sufficient it is desired also to produce a compression in a direction at right angles to the direction of action of the draw-rods *h*, such pressure may be obtained without its being 85 90 95 100

necessary to employ separate draw-rods arranged longitudinally to the side bars *f*. For this object an angle-piece or hook *n*, Fig. 5, may be arranged at each of the four free ends 5 of the side frames *f*, which angle-pieces are connected together in pairs by removable draw-rods *o*, which may be drawn up by tightening their nuts *p*. The arms *q* of the said hooks or angle-pieces *n* thus exert a 10 pressure (in the direction indicated by the arrow in Fig. 5) against the free outer sides of the sieve-frame and provide for a firm pressing together in this direction of the oscillating parts.

15 Instead of employing draw-rods *o* such as just described an arrangement such as is shown in Fig. 6 may be adopted, in which by turning a screw *r*, which passes through one arm of an elbow-lever *s* and bears against the 20 bar of the U-iron side piece, said elbow-lever *s* is turned in the direction indicated by the arrow, so as to press against the frames longitudinally without exerting any force which would tend to counteract the clamping ac- 25 tion of the side bar *f*, upon the end of which said elbow-lever is pivoted.

It is evident that where screws are men-

tioned equivalent elements may also be em- 30 ployed—such, for instance, as eccentrics, wedges, cams, or the like.

I declare that what I claim is—

1. In a plan sifter, a plurality of side bars, means for drawing said side bars together, a plurality of sifting-frames arranged between said side bars, angle-pieces upon the ends of 35 said side bars, and means for operating said angle-pieces, whereby they are adapted to retain said sifting-frames in position.

2. In a plan sifter, a plurality of side bars, means for drawing said side bars together, a 40 plurality of sifting-frames arranged between said side bars, angle-pieces upon the ends of said side bars, and draw-rods connecting the angle-pieces upon the ends of said side bars, for operating said angle-pieces whereby said 45 angle-pieces serve to retain said sifting-frames in position.

In testimony whereof I have hereunto set my hand in presence of two subscribing witnesses.

JULIUS KONEGEN.
